UNITED STATES PATENT OFFICE.

JOSEPH L. STILLMAN, OF FRESNO, CALIFORNIA.

CAR-COUPLING.

SPECIFICATION forming part of Letters Patent No. 439,982, dated November 4, 1890.

Application filed March 18, 1890. Serial No. 344,332. (No model.)

To all whom it may concern:

Be it known that I, JOSEPH L. STILLMAN, residing at Fresno, in the county of Fresno and State of California, have invented certain new and useful Improvements in Car-Couplings, of which the following is a specification.

My invention relates to automatic car-couplings; and it has for its object to provide a coupling of this class which will be simple in construction, easy to manipulate, and positive in its desired operation.

To this end my invention consists in certain novel combinations and peculiar arrangement of parts, all of which will herein-after be fully described in the annexed specification, and particularly pointed out in the claims, reference being had to the accompanying drawings, in which—

Figure 1 is a perspective view of my improved car-coupler. Fig. 2 is a central vertical longitudinal section thereof. Fig. 3 is a cross-section on the line 3 3, Fig. 2; and Fig. 4 is a detail view of the several parts detached.

In the accompanying drawings, A indicates the draw-head, which is secured to the car-body in any well-known manner, which is provided with the usual flaring mouth or opening a, the upper wall of which is extended downward, as at a', whereby the height of the link-opening a² is of a size slightly greater than the thickness of the link. The link-opening a² communicates at its rear end with a vertical chamber B, formed in the top of the draw-head, such chamber being composed of two compartments C D, in the forward one of which is located a link-holding device E, while in the rear end thereof is located the head or abutment-face of the spring-buffer F, against which the inner end of the link strikes during the act of coupling.

The spring-buffer F, which is clearly shown in Fig. 4 of the drawings, consists of the head f, the rearwardly-extending stem f', which operates in a socket G in the draw-bar, and of vertical stem f², which plays in an elongated slot h in the guide-block H, held in the chamber D, its lower face engaging the horizontal shoulders d d, the front face being held from outward movement by the vertical shoulders d' d', as shown.

I denotes a coiled spring disposed about

the stem f' and held in place by the rear wall of the head f and the shoulder g in the draw-bar socket G.

55

The link holder or presser E, which is also clearly shown in Fig. 4 of the drawings, and which is held to slide vertically in the compartment C, consists of the base or body portion e, formed with a vertical semicircular recess e' on its front face, which, in connection with a similar recess a⁵, formed in the front wall of the compartment C, constitutes the coupling-pin aperture.

60

e² e² denote stems projected upward from the base e, which pass through apertures e³ e³ in a cross-bar J, secured in sockets j j in the draw-head, said stems being supported from said cross-bar by means of the pins j² j², passed through the apertures j³ j³, as shown. K denotes coiled springs disposed about the stems e² e², which serve to normally force the link-holder downward, the lower front edge e⁵ of said holder being beveled to form a continuation of the upper wall of the mouth of the draw-head, as most clearly shown in Fig. 2 of the drawings.

65

The rear wall 10 of the chamber B is extended upward and forms a guideway for the lower extension 11 of a housing 12, formed into a continuation of the chamber B, such housing completely covering the said chamber, the lower front edge of which is formed with a semicircular recess 13, arranged in the same vertical plane with the recess in the link-holder.

70

L denotes a removable cap-plate secured upon the upper face of the housing 12, the front end of which is extended over the front wall of the housing, such end being formed with a semicircular recess 15, disposed over the recess 13.

75

M denotes a sliding plate, the front edge of which is also formed with a semicircular recess m, said plate being disposed to operate just below the cap-plate L, such plate passing through an opening m' in the front wall of the housing and normally projecting slightly in advance of the recess 15 in the said cap-plate. The rear end of said plate is formed with an aperture m², which fits over a stud m³, which projects from the stem f', said stem projecting up into the housing, as shown.

80

N denotes the coupling-link, which is of

the ordinary construction, its horizontal faces being slightly flattened; and O denotes the coupling-pin, which is provided with the head o, formed into an annular enlargement, which 5 limits the downward movement of said pin, and also serves as a convenient means for holding said pin in its upper or uncoupled position, such position being effected by adjusting said link upward, so that the rear portion 10 of its annular flange 20 will rest upon the end of the plate M, being held when so adjusted from accidental displacement by means of a hood P, hinged at its rear end to the cap-plate L, its forward end when swung down 15 adapted to engage the outer face of the pin-head and thereby hold same in place.

The operation of my improved coupler is as follows: When the pin is held in its uncoupled position, as shown in Fig. 2, the plate 20 M will be in its outermost or normal position, serving, in connection with the hinged hood P, to hold said pin from accidental displacement. Now, as the adjacent draw-head approaches, its link will enter the mouth a', engage 25 and slightly raise the link-holder, and strike against the yielding abutment-plate and force it inward. Such movement of the plate will move the plate L inward, and thereby permit the pin to drop and couple 30 with the link.

Having thus described my invention, what I claim, and desire to secure by Letters Patent, is—

1. The combination of the draw-head A, 35 provided with a vertical chamber B, communicating at its lower end with the link-opening a, a spring-actuated link-presser held to slide vertically in said chamber, a spring-actuated abutment held to slide horizontally 40 in said chamber, the coupling-pin, a movable pin-support located above the draw-head, and a connection between said support and the yielding abutment, substantially as and for the purpose described.
- 45 2. The combination, with the draw-head A, provided with the mouth a, the upper wall thereof formed into a downward extension,

and with a vertical chamber B, communicating with said mouth a, of the yielding link holder or presser, consisting of the base e, 50 formed with a beveled front edge e⁵, projecting into the link-opening, the upwardly-projecting stems e² e², the cross-bar J, adapted to be fixedly secured to the draw-head, and the springs for normally holding said device in its 55 lowermost position, all arranged substantially as and for the purpose described.

3. A car-coupling consisting of the draw-head formed with the usual link-opening a and coupling-pin, a movable pin-support disposed above the draw-head, a yielding abutment located at the rear of the link-opening adapted for horizontal movement therein, intermediate connections between said abutment and pin-support, and a spring-actuated 60 link holder or presser vertically movable in the draw-head in advance of the link-abutment, substantially as and for the purpose described.

4. The combination, with the draw-head A, 70 provided with the usual pin-aperture and link-opening, and the coupling-link provided with an annular flange or head, of a housing secured upon the draw-head, a pin-support held to slide horizontally in said housing, its 75 forward end projected beyond the front wall of the housing, provided with a semicircular recess in its end disposed normally over the pin-aperture in the draw-head, said recessed end adapted to project under the flanged 80 head of the pin, a horizontally-movable yielding abutment located within the draw-head adapted to be engaged by the link, a connection between said abutment and the pin-support, and the hood P, hinged upon the upper 85 face of the housing and adapted to swing over the head of the pin when held up by its supporting-plate, substantially as and for the purpose described.

JOSEPH L. STILLMAN.
